UNITED STATES PATENT OFFICE.

SPENCER H. LOGAN, OF CHICAGO, ILLINOIS.

CIGARETTE-HOLDER.

1,368,173.

Specification of Letters Patent. Patented Feb. 8, 1921.

Application filed April 19, 1919. Serial No. 291,339.

To all whom it may concern:

Be it known that I, SPENCER H. LOGAN, a citizen of the United States, and a resident of Chicago, in the county of Cook and State 5 of Illinois, have invented certain new and useful Improvements in Cigarette-Holders; and I do hereby declare the following to be a full, clear, and exact description of the invention, such as will enable others skilled 10 in the art to which it appertains to make and use the same.

My invention relates to an improvement in cigarette holders, the object being to provide a simple attachment for ejecting the 15 cigarettes from the holder and for supporting and elevating the end of the holder when the latter is resting on a table or other support, and it consists in the parts and combination of parts as will be more fully explained and pointed out in the claims.

In the accompanying drawings, Figure 1 is a view in elevation of the holder with a cigarette therein. Fig. 2 is a similar view showing the cigarette ejected. Fig. 3 is a 25 view in longitudinal section through the holder, the ejector being in its normal position. Fig. 4 is an enlarged view of the outer end of the holder showing the ejector in the position shown in Fig. 2. Fig. 5 is a view 30 in transverse section on the line $\alpha-\alpha$ of Fig. 4. Fig. 6 is a view in longitudinal section of the outer end of the holder showing the slot and groove, the ejector being removed. Fig. 7 is a view in transverse section on the 35 line $y-y$ of Fig. 6, and Fig. 8 is a view in perspective of the ejector and finger piece, the parts being shown detached.

1 represents the holder, which may be of any of the shapes, styles or materials now in 40 use, and adapted for either cigars or cigarettes. This holder is provided adjacent its outer or cigarette receiving end with a closed slot 2 which should be of a length to permit of sufficient movement of the ejector to dislodge and eject the cigarette, and it is also provided on its inner face in the plane of the slot, with a shallow groove 3 in which the stem 4 of the ejector rests and moves and in which said stem is guided. This stem, 45 which may be made of any suitable material, preferably metal, is of a size to fit within said groove without projecting to any extent into the holder, and is considerably larger than the slot so as to cover the latter 50 when the ejector is in its normal position. Secured to the stem 4 near its lower end is

the ejector 5, which projects into the cavity of the holder and which may form a stop or abutment for the cigarette. Its normal location, as shown in Fig. 3, is sufficiently far 60 back from the larger end of the holder to permit the cigarette to be entered and securely held by the holder, and as above stated it may act as a stop for limiting the penetration of the cigarette. This ejector is 65 adapted to be moved forwardly in the holder and by engagement with the inner end of the cigarette push the latter forwardly sufficiently to dislodge and free it from the holder.

The stem 4 projects at the rear of the ejector, as shown in Fig. 4, so as to cover slot 2 when the ejector and stem are moved forwardly, and prevent the entrance of air through the slot, and in order to more effectually close the slot, I prefer to provide the outer face of the stem 4 with a cover or lining 6 which may be of asbestos or other material which will effectually seal the slot 2 when the ejector is in its normal position 80 and also when more or less in advance of its normal position and thus prevent any air from being drawn in except that which passes through the cigarette. The stem 4 is provided at 7, with a rectangular enlargement 85 which fits in the slot 2 and operates to limit the extent of longitudinal movement of the stem. This enlargement terminates approximately flush with the outer face of the holder and is provided with pins 8 90 adapted to enter holes in the curved plate 9 and be secured to the latter by upsetting the ends of the pins. This plate may however be secured to the enlargement 7 by screws or in any other preferred manner and is curved 95 to conform to the contour of the outer face of the holder over which it is moved. This plate 9 carries the knobs or finger pieces 10 by which the ejector is actuated, and these finger pieces are preferably in the form of 100 two balls separated sufficiently to form a support for the holder when the latter is placed on a table or other article. Any other shaped finger piece having a widened base to support and elevate the outer end 105 of the holder may be used.

It is the purpose of this device to make possible the free removal of the cigarette when the latter has been smoked close up to the mouth of the holder, and by making the 110 finger piece of two separate parts, such as knobs or prongs that will elevate the end of

the holder, the latter may be placed on a table or other article without fear of burning or injuring the latter. Again, by constructing the parts so that the slot is closed 5 at all times when a cigarette is being smoked, the holder will be practically as air tight as the ordinary holder.

As many obvious changes could be made 10 in the above described invention and many 15 widely different embodiments of this invention might be made without departing from the scope thereof, I desire it to be understood that the matter contained in the above 20 described structure and shown in the accompanying drawings, is to be taken as illustrative and not in a limiting sense.

Having fully described my invention what 25 I claim as new and desire to secure by Letters-Patent, is:

1. As a new article of manufacture a cigarette holder provided adjacent its outer end with a slot, an ejector mounted to move in said slot, and a finger piece connected with the ejector for actuating the latter, the 30 said finger piece having a widened base to form a support for holding the outer end of the holder elevated and prevent the same from rolling.

2. A cigarette holder provided adjacent 35 its outer end with a slot, a stem within the holder and covering said slot, the said stem being of greater length than the slot, an ejector secured to the stem intermediate the ends of the latter, and a finger-piece outside 40 of the holder and connected through the slot with the stem intermediate the ends of the latter, whereby the slot will be covered by

the stem throughout the movements of the latter.

3. A cigarette holder provided adjacent 45 its outer end with a groove and a slot within the groove, a stem mounted to slide in the groove, an ejector on said stem, and a finger piece having connection through the slot with the stem for moving the latter, the 50 said finger piece having a wide base to form a support for holding the outer end of the holder elevated and prevent the same from rolling.

4. A cigarette holder having a slot, an 55 ejector disposed in said holder and having a part movable in said slot, and a combined finger piece for said ejector and a widened support for the holder to hold the outer end of the latter elevated and prevent said 60 holder from rolling.

5. A cigarette holder provided with a groove in its inner face and a slot in the grooved portion intermediate the ends of the latter, an ejector having a stem movable 65 in the groove, a lining on said stem and covering the slot, and a finger-piece passing through the slot and attached to the stem intermediate the ends of the latter whereby the slot will be covered by the lining throughout the movements of the stem.

In testimony whereof, I have signed this specification in the presence of two subscribing witnesses.

SPENCER H. LOGAN.
